CLAIM

The ornamental design for a rally cap, as shown and described.

DESCRIPTION

FIG. 1 is a front perspective view of a first embodiment of the rally cap according to the present invention;

FIG. 2 is a rear perspective view of a first embodiment of the rally cap according to the present invention as shown in FIG. 1 with the closure device in an open position;

FIG. 3 is a front elevation view of a first embodiment of the rally cap according to the present invention as shown in FIG. 1;

FIG. 4 is a rear elevation view of a first embodiment of the rally cap according to the present invention as shown in FIG. 1 with the closure device in an open position;

FIG. 5 is a side elevation view of a first embodiment of the rally cap according to the present invention as shown in FIG. 1;

FIG. 6 is a side elevation view of a first embodiment of the rally cap according to the present invention as shown in FIG. 1, shown from the opposing side view as that shown in FIG. 5;

FIG. 7 is a top plan view of a first embodiment of the rally cap according to the present invention as shown in FIG. 1 with the closure device in an open position;

FIG. 8 is a bottom plan view of a first embodiment of the rally cap according to the present invention as shown in FIG. 1 with the closure device in an open position;

FIG. 9 is a rear perspective view of a first embodiment of the rally cap according to the present invention as shown in FIG. 1 with the closure device in a closed position;

FIG. 10 is a bottom plan view of a first embodiment of the rally cap according to the present invention as shown in FIG. 1 with the closure device in a closed position;

FIG. 11 is a rear perspective view of a second embodiment of the rally cap according to the present invention as shown in FIGS. 1-10 with the closure device in an open position, it being understood that the portions shown in broken lines and lettering are for the purposes of illustrating environment and form no part of the design sought to be patented; and,

FIG. 12 is a top plan view of a second embodiment of the rally cap according to the present invention as shown in FIGS. 1-10 with the closure device in an open position, it being understood that the portions shown in broken lines and lettering are for the purposes of illustrating environment and form no part of the design sought to be patented.

The broken lines that represent stitching form no part of the claimed design.
